UNITED STATES PATENT OFFICE.

CHARLES E. VANCE, OF TULSA, OKLAHOMA.

GASKET CUTTER.

Application filed May 19, 1922, Serial No. 562,138. Renewed December 11, 1924.

To all whom it may concern:

Be it known that I, CHARLES E. VANCE, a citizen of the United States, residing at Tulsa, in the county of Tulsa and State of Oklahoma, have invented certain new and useful Improvements in Gasket Cutters, of which the following is a specification.

This invention is for a gasket cutting device, and has for its primary object to provide a device for this purpose which is relatively simple and durable and which may be cheaply constructed and easily operated.

Further important objects of the invention are to provide a cutter which may be used to cut circular or oval gaskets and which has adjustable cutting knives of improved construction.

In my co-pending application Serial No. 430,612 of December 14, 1920, I show a gasket cutter of a heavier type carried in a supporting frame in such manner that it may be moved about to cut from different parts of a sheet of material. The present invention, which is designed to provide a lighter machine for use where a large device is not necessary, is fixed and the sheet must be moved relatively thereto, the device providing clamping means for the sheet of fabric.

My invention may be understood by referring to the accompanying drawings, in which:

Fig. 1 shows a top plan view of a preferred form of my invention;

Fig. 2 shows a side view, partly in section and partly in elevation, of the machine;

Fig. 3 is a transverse sectional view on line III—III of Fig. 1;

Fig. 4 is a view similar to Fig. 1 of a modification, with part thereof broken away;

Fig. 5 is a view similar to Fig. 2, of the modification shown in Fig. 4.

Referring to Figs. 1 to 3 of the drawings, 5 indicates a bed or table top of suitable construction, through which projects a central shaft or stud 7 having a head 8, a threaded part 9, a reduced portion 10, threaded at 11, and a pointed upper end 12. Suitably positioned relatively to the central stud 7, are one or more, preferably two, stud holders 13 having flanged lower ends 13^a. In these holders are studs 14, having a reduced portion 15 and pointed upper ends 16.

The central stud 7 and the holding pins or studs 14 project through the table covering 55 17 of wall board or other suitable material.

The central stud and the holding pins are passed through the fibre sheet A, from which the gaskets are to be cut, when the cutter is being used, as shown in Fig. 2, and serve to 60 hold the sheet against relative movement.

A plate 20 is removably positioned on the central stud, said plate having an opening 21 therein through which the stud passes. The plate also has openings 22 therein to receive the projecting upper ends of the pins 14. The plate has a groove or cam track 23 therein which corresponds to the shape of the gasket to be cut. As shown in the drawings, the cam track is of an oval shape. The 70 plate, when in position, is held against rotation by the pins 14. It may be clamped down against the fabric by a nut 24 screwed onto the threaded portion 9.

Surrounding the reduced portion 10 of the 75 central stud, is a sleeve 25, and screwed onto the threaded part 11 is a hand nut 26.

The cutter moving mechanism comprises a substantially horizontal arm 27 having an elongated slot 28 therein, through which 80 passes the central stud and the sleeve 25, the slot having a width substantially equal to the diameter of said sleeve.

Passing through the arm is a vertical pin 29 preferably having a roller 30 on its lower 85 end which engages in the cam track 23. The pin 29, which is preferably of the same diameter as portion 10 of the central stud, is slidable vertically with relation to the arm, and is surrounded by a compression 90 spring 31 which urges the arm upwardly.

The outer end of the arm is equipped with a handle 32. The arm has a second longitudinal slot 33 therein, the tops of the sides of the slot being flattened, as indicated at 95 34. This slot is for the purpose of receiving adjustable cutters.

The cutters comprise cutting disks 35 pivotally mounted in the forked end of a post 36 which is swivelled in a supporting 100 sleeve 37. This sleeve has a lateral projection at each side at its bottom, designated 37^a, on which projects one guide portion 37^b for slidably engaging the arm 27. The top of the post 36 has a nut 36^a by means of 105 which the post is held in place and which,

if desired, can be tightened against the top of the sleeve 37 to hold the post against rotation. The top of the sleeve is threaded to receive a lock nut 38, which nut has a handle 5 39. This lock nut may slidably engage the top portions 34 of the sides of the slot. By tightening the nut, the sleeve may be locked or clamped against sliding. A simple adjustment for the cutters is thus provided.

10 By reason of the swiveled mounting for the cutters, the cutters are enabled to turn when cutting oval or non-circular gaskets.

In operation, the sheet is properly positioned on the table, with the central stud 7 and pins 14 passed therethrough. Plate 20 is then clamped into position by nut 24, and the other parts are assembled, the roller 30 on pin 29 engaging in the cam slot 23 of plate 20. Cutters 35 are adjusted to cut the 20 gaskets of the desired size and handle 32 is then moved. By reason of the arm 27 being reciprocable longitudinally relatively to central pin 7, the cutters will be moved in a path corresponding to the shape of cam track 23, through the action of pin 29 and roller 30. In the device shown, the gasket would be an oval. By suitably changing the cam track, different shapes of gaskets may be made.

30 When it is desired to make a circular gasket, with the form of machine shown in Figs. 1 and 2, the pin 29 is removed and the end of central stud 7 is passed through the opening in the arm through which pin 29 is ordinarily passed. The arm then pivots about stud 7 as a center, and the path of the cutters is a circular one.

Figs. 4 and 5 show a modification designed for cutting only circular gaskets. In 40 this form of machine, 40 is the table, 41 the covering therefor, and A' the fabric from which the gasket is cut. The central stud 42 corresponds to stud 7 described in connection with Figs. 1 and 2, having a head 45 43, a threaded intermediate portion 44, a reduced portion 45, a threaded part 46, and a pivoted end 47.

Screwed on the intermediate threaded part 44 is a clamping nut 48. Surrounding the 50 shaft and resting on the clamping nut is a spring 49.

The arm 50 is journalled at 51 about the portion 45 of stud 42. The arm is longitudinally slotted, as indicated at 52 to receive 55 the adjustable cutter supporting means 53, which may be similar to those hereinbefore described. The spring 49 yieldably supports the arm and hand wheel or nut 54 threaded onto part 46 serves to hold the arm down against the action of the spring.

The device is operated in the same way as the device shown in connection with Figs. 1 and 2, but may be used to cut circular gaskets only.

65 Various changes and modifications may be

made in my invention within the scope of the appended claims.

What I claim is:

1. A cutting machine comprising a supporting structure having a top, a stud 70 mounted on said supporting structure and projecting above said top, an arm, said arm having a slotted opening and a round opening therein through either of which said stud may be projected, means for guiding 75 the arm when the stud is projected through the slotted opening, and cutting means on said arm.

2. A cutting machine comprising a supporting structure having a top, a stud 80 mounted on said supporting structure and projecting above said top, an arm, said arm having a slotted opening and a round opening therein through either of which said stud may be projected, means for guiding 85 the arm when the stud is projected through the slotted opening, and adjustable swiveled cutters on said arm.

3. A machine for cutting non-circular gaskets comprising a supporting structure 90 having a substantially flat top, a fixed central vertical stud on said top, a small vertical stud at one side of the central stud, a removable cam plate having a track therein fitted around the central stud and engaged by the small stud whereby said cam plate is held against rotation, a clamping nut on the central stud for clamping the cam plate down, a removable arm having a slot therein through which the central stud 100 extends, cutters on the arm, means on the arm engaging in said track in the cam plate to guide the arm, and removable means for retaining the arm in position about the stud. 95

4. A machine for cutting non-circular gaskets comprising a supporting structure having a substantially flat top, a fixed central vertical stud on said top, a small vertical stud at one side of the central stud, a separate removable cam plate having a track therein fitted around the central stud 105 and engaged by the small stud whereby said cam plate is held against rotation, a removable clamping nut for clamping the cam plate down, a removable arm having a slot 110 therein through which the central stud extends, adjustable cutters on the arm, means on the arm engaging in said track in the cam plate to guide the arm, and removable means for retaining the arm in position about the stud. 115

5. The combination with a substantially flat supporting table having a non-rotatable stud secured thereto and projecting upwardly therefrom, a pin carried by the table at 125 one side of the stud, said stud being threaded intermediate its ends and at its upper end, a plate having a central opening therein passed over the stud, a clamping nut on said stud screwed to the intermediate 130

threaded portion thereof, and serving to normally confine said plate against upward movement, an arm having a slot therein through which the stud extends, removable

means on the upper threaded end of the stud for holding the arm against upward movement, a cutter on the arm, and cooperating

means on the plate and arm for guiding the arm, said plate having a recess therein into which the pin engages to hold the plate 10 against rotation.

In testimony whereof I hereunto affix my signature.

CHARLES E. VANCE.
